GEORGE F. NEWTON, OF KANSAS CITY, MISSOURI.

ADJUSTABLE ROD-CLAMP.

1,378,267.

Specification of Letters Patent. Patented May 17, 1921.

Application filed March 21, 1918. Serial No. 223,854.

To all whom it may concern:

Be it known that I, GEORGE F. NEWTON, a citizen of the United States, residing at Kansas City, in the county of Jackson and 5 State of Missouri, have invented certain new and useful Improvements in Adjustable Rod-Clamps, of which the following is a specification.

This invention relates to adjustable rod 10 clamps and has for its object to produce a two-member clamp of such construction that it can be easily and quickly so embedded at a plurality of points in an iron rod or the like, that it shall be impossible for the latter to slip or move endwise under any pull 15 short of that capable of stripping a shaving from the rod.

A further object is to produce a two-member clamp adapted to secure a rod or 20 the like, firmly in place under the application of a blow on one of the members.

A still further object is to produce a 25 clamp comprising a tubular member to be fitted on a rod and a slidable wedge member extending cross-wise through the tubular member and adapted when advanced, to 30 bend the rod where the same is inclosed by the tubular member, and thus lock the rod against endwise movement through the member.

With these general objects in view the invention consists in certain novel and useful features of construction and combinations of parts as hereinafter described and 35 claimed; and in order that it may be fully understood reference is to be had to the accompanying drawing, in which:

Figure 1, is a central vertical section of a 40 part of a concrete mold and a two part clamp embodying my invention, the clamp being shown as mounted operatively upon a reinforced rod extending through the mold.

Fig. 2, is a section on the line II—II of 45 Fig. 1.

Fig. 3, is a detailed perspective view of the clamp.

Fig. 4 is a face view of the wedge.

In the said drawing, 1 indicates one side 50 of a concrete mold of any suitable type, 2 indicates a reinforce or stiffening bar for the mold 1, and 3 indicates a reinforce rod extending transversely through the mold for the purpose of reinforcing the concrete 55 wall or the like, 4, produced in the mold.

The drawing shows a fragment of only

one side of the mold, but as customary, it is necessary to provide means for preventing expansion of the mold under the pressure applied by the concrete as the same is deposited and tamped therein. 60

Various appliances for guarding against expansion of the mold by engagement with the outer side of the same and the reinforce rods, have been employed, and among other 65 appliances collars have been fitted on the projecting ends of the rods, provided with set screws for clamping the rods against the collars at one side of the passage thereof. I have found that to guard against slippage 70 of the rod or expansion of the form in high walls or tall columns or the like, it is essential to effect embedment of the clamping devices into the rod at a plurality of points and that the rods shall be slightly bent 75 between the most remote points where embedment occurs.

In my preferred construction I employ a collar 5 having its inner or form-engaging end broadened by flanging it outward at 80 6. The collar is provided with a through passage 7 for loosely receiving the projecting end of a rod 3. The upper half of the passage is preferably rounded and the lower half is of substantially V-shape, in cross 85 section, 8 indicating the covering walls of the lower half of the passage, and projecting upward from said walls 8 and spaced a suitable distance apart are sharpened and preferably parallel ribs 9. 90

The collar is preferably formed at its upper side, that is at the side diametrically opposite the ribs 9, with an enlargement 10, and extending through the collar and the said enlargement thereof is a transverse 95 passage 11, the same communicating with the passage 7 and tapering from one end to the other, the taper occurring at the upper side of the slot or passage 11, so that when a wedge shaped key 12, fitting in said 100 slot or passage is advanced therein through the application of a blow or the like on its broad end, the wedge key shall be caused to move downward and thereby apply downward clamping pressure on the rod extending through the lower part or half of the passage 7, it being noted in this connection that the wedge key is disposed in a plane between the planes of ribs 9, so that said wedge key when advanced as explained, shall slightly bend or kink the rod 105 downward between said ribs, and in such 110

action cause said ribs to embed themselves in the lower part of the rod at opposite sides of its axis, the embedment of said ribs in the rod producing notches 13 in the latter.

5 In order that the wedge key member of the clamp may not only bend the rod downward as explained, but also embed itself therein vertically above the axis of the rod, the lower edge of the wedge key is beveled 10 laterally to produce a sharpened edge 14, the kerf formed in the rod by the key producing a substantially abrupt shoulder 15 at the outer side of the key, so that it shall be impossible for the collar to slip toward 15 the outer end of the rod, unless the force tending to effect such movement is sufficient to strip shavings off the rod from the wedge key at the top and the innermost rib at the bottom, it being understood that the taper 20 of the wedge key will be such that the rod would be stripped as explained, before the wedge key could work backward through the passage or slot 11.

This adjustable rod clamp may be made 25 in various sizes though it is preferable that each clamp shall be susceptible of use on rods of different sizes, it being noted that the V-shaped part of passage 7, centralizes the collar member on the rod, as distinguished from a round passage, in which a small rod would have a chance for undesirable lateral play or movement. In Fig. 2, the dotted inner circle represents a rod of 30 large diameter, and the dotted lines of the wedge key indicates substantially the position of the latter when fully advanced to hold the collar in a fixed position on the large rod, so that neither the one nor the other can slip.

40 The wedge key is provided at its small or narrow end with a lateral protuberance 16 incapable of passing through said slot, for the purpose of guarding against the accidental dislocation of the wedge key from the 45 tubular member.

The flange 6 is provided with a pair of holes 17 through which nails may be driven 50 into the form preliminary to performing the clamping function, the nails in this event serving to hold the clamping device in proper relation to the rod upon which it is fitted during the clamping operation. The clamping device of course, can be held by hand in such position during the clamping 55 operation, but the use of the nails makes the work easier and expedites the same.

One of the chief functions of the nails is to hold the clamping device, that is the collar member thereof against accidental 60 movement with respect to the holes in the form so that a long section of the latter may be taken down and reerected without putting the operators to the labor of removing and replacing each individual clamping device. In a large building this will obviate

the necessity of handling hundreds of individual clamping devices each day and will thus save the contractor erecting the building or wall a large amount of time and money, as when a section equipped with a 70 large number of forms is properly placed, the holes in the forms and the passages in the clamping device will be properly aligned so that the rods can be readily slipped in position, and then each clamping device is 75 clamped as explained, rigidly upon its respective rod.

As it is impossible by hand pressure to force and hold the collar against the form to close all joints therein as tightly as desired, I have provided a tightener for interposition between the form and collar, this tightener to be driven home by the blow of a hammer. The tightener is in the form of a wedge 18, and the same is forked to straddle the rod and guard against tilting the collar. I have found however, that a forked wedge, unless unduly large and heavy, will not perform its function efficiently because of the tendency of the legs to spread apart 90 under the resistance offered by the form and collar, and to overcome this difficulty provision is made for interlocking the legs and collar as regards lateral movement of either. The preferred method of thus interlocking 95 said parts, is to make the legs substantially V-shape in cross section and produce downwardly-tapering and substantially V-shaped grooves 19 in the inner face of the collar, it being noted that the grooves 19 enable the 100 operator to fit the points of the wedge between the form and collar without necessitating the use of a tool or of employing force as would otherwise be necessary. After the wedge is thus started it can be instantly 105 driven home by means of a hammer, and thus subserve the function of a tightener. When the concrete wall or the like is set, a blow applied on the small end of the key 110 12 with a hammer, will loosen the collar and wedge simultaneously. A tightener of this character facilitates the work of setting up a form and permits of the use of much shorter reinforce rods than that type of tightener 115 which must be mounted on the rod outward of the collar.

From the above description, it will be apparent that I have produced an adjustable rod clamp and tightener embodying the features of advantage set forth, and while 120 I have illustrated and described the preferred construction, it will be understood that I reserve the right to make such changes in the form, proportion, detail construction and arrangement of the parts, as properly 125 fall within the spirit and scope of the appended claim.

I claim:

An adjustable rod clamp, comprising a 130 tubular member to be fitted loosely on a

rod, the sides of the lower portion of the passage of said member, converging downward to a point and each of said sides having a pair of V-shaped sharpened upwardly 5 projecting transverse ribs, the ribs being ratchet-toothed shape in cross section and disposed with their abrupt faces facing outwardly, said member also having a transverse slot intersecting its passage and occur-

ring in a plane between the planes of said 10 ribs, and a wedge fitting in the said slot and having a downwardly and outwardly beveled lower edge for embedment in and transversely of the upper side of the said rod and for bowing the latter downward between the 15 said ribs and embedding it on said ribs.

In testimony whereof I affix my signature.
GEORGE F. NEWTON.
